UNITED STATES PATENT OFFICE.

PASQUALE DELLA TORRE, OF PHILADELPHIA, PENNSYLVANIA.

CABINET FOR PHONOGRAHS AND THE LIKE.

Application filed January 24, 1923. Serial No. 614,530.

To all whom it may concern:

Be it known that I, PASQUALE DELLA TORRE, a subject of the King of Italy, (having resided in the United States one year 5 last past and having declared his intentions of becoming a citizen thereof,) residing in the city and county of Philadelphia, State of Pennsylvania, have invented a new and useful Cabinet for Phonographs and the like, 10 of which the following is a specification.

My invention relates to a cabinet or case of a phonograph, talking machine or the like, and consists in adapting the top of the cover thereof to form a table which is movable out of the paths of the cover in its opening and closing motions so as not to be engaged by said cover nor to disturb an object which may be placed on the table.

The invention is satisfactorily illustrated 20 in the accompanying drawing, but the important instrumentalities thereof may be varied, and so it is to be understood that the invention is not limited to the specific details shown and described, as long as they 25 are within the spirit or scope of the claims.

Figure 1 represents a top or plan view of the portion of a cabinet embodying my invention.

Figure 2 represents a vertical section 30 thereof on line 2—2 Figure 1.

Figure 3 represents a similar section thereof, the cover being raised or open.

Figure 4 represents a front elevation of 35 detached portions.

Figure 5 represents a bottom plan view of the table of the device.

Figure 6 represents a transverse section on line 6—6 Figure 5, on an enlarged scale.

Figure 7 represents a perspective view of 40 the locking mechanism of the table.

Figure 8 represents a vertical section of the hinge portion of the cover.

Figure 9 is a cross section through the 45 table and cover showing the hinge construction.

Similar numerals of reference indicate corresponding parts in the figures.

Referring to the drawings,

1 designates the top portion of a cabinet 50 of a phonograph or the like, and 2 designates the cover or lid thereof, the latter being hinged thereto as at 3 and being of chambered or hollow form.

4 designates the upper member or wall of 55 the cover, the same forming a table on which

may be placed a vase, ornament, figure, or other object so as to be stood and supported thereon, it being noticed that said member is separate from the surrounding side wall 5 of said cover leaving at the top of the cover the opening 6 which may be occupied by said table in the normal position of the cover, so as to close said opening at the top proper of the cover, as most plainly shown in Figure 2.

The table 4 is slidably supported on 60 standards or brackets 7 which are of double elbow form, the lower horizontal limbs 8 whereof are secured to the horizontal rim 9 in the top portion of the cabinet and the upper horizontal limbs 10 are freely fitted in 65 guides 10* which are stationarily secured to the underside of the table 4 and slidable therewith.

The brackets 7 are strengthened by the 70 curved or angular braces 11 which are secured respectively to the limbs and sides of said brackets, the effect of which is evident.

At or about the centre of the table 4 on the underside thereof is secured the forward end 75 of the strap or plate 12, the rear end whereof is connected with one leaf 13 of the hinge 14, the other leaf 15 whereof is secured to the inner face of the side wall of the cover 2, it being seen that said hinge 14 of the strap is eccentric to the hinge 3 of the cover.

Pivotedly connected with the underside 80 of the table is the spring pressed catch 16 on whose side is the detent 17 which is adapted to enter the recess 18 in the adjacent upper limb 10 of a bracket 7, and so 85 hold the table immovable when it is in the position shown in Figure 3, the cover then being in raised or open condition.

It will be seen that in the normal condition of the cover, the table 4 forms a closing top therefor and is adapted to support the vase, etc., as shown in Figures 1 and 2.

When the cover is to be opened it is raised as usual, turning on the hinge 3. Then the hinge 14 is carried with the cover, 100 in the present case to the right, and with it the strap 12 whereby it draws the table 4 to the right, when said table especially at its front recedes from the adjacent side wall of the cover 2 whereby as the cover describes its circle said wall is removed from contact with the table and so passes freely over the latter and consequently over the vase or object on the table without contacting with said object or upsetting or knock- 105 110

ing it from the table, as apparent in Figure 3. The interior of the cabinet is then accessible as usual in phonographs or the like.

In closing the cover the catch 16 having been duly operated to be unlocked from the upper limb of the bracket the cover rides freely over the object and table without contacting therewith or disturbing it, and the table is returned to its normal position, in the present case, to the left by the action of the strap 12 which is moved in similar direction by the lowering of the cover. Then as the cover closes, the opening 6 is positioned as to receive the table 4 when the latter enters said opening, and so said opening and consequently the top of the cover is fully closed, said table now again comprises the upper member or wall of the cover as hereinbefore stated and apparent in Figure 2.

If desired records, books, papers, etc., may be placed on the table as a support therefor, and they will not be in the path of the cover in its opening and closing motion and so remain undisturbed.

Having thus described my invention what I claim as new and desire to secure by Letters Patent, is:—

1. A cover for a cabinet of the character stated having its top portion separate from the surrounding side wall forming a table, means on the cabinet for supporting said table, and means connected with said cover and table for moving the latter when the cover is opened and closed out of the paths of the same without having said table and an object thereon contacted by said cover.

2. A cover for a cabinet of the character stated having in its top an opening, and a separate section for said top which is adapted to occupy said opening as a closure there-

for forming a table for supporting an object thereon, and means hinged to said cover and connected with said section adapted to operate said table in the opening and closing motions of said cover whereby it is removed out of the paths of said cover in said motions. 45

3. A cover for a cabinet of the character stated having in its top an opening and a separate section which is adapted to occupy said opening and forming a closure therefor, and a supporting table, means on the cabinet for sustaining said table, and a connection with said table and cover whereby the latter in its opening and closing motions is adapted to operate said table in the cover clear of the latter in said motions. 50

4. A cover for a cabinet of the character stated having in its top an opening, and a section separate from the surrounding side wall of the cover adapted to occupy said opening and form a closure therefor and comprise a table, means on the cabinet for movably sustaining said table, guides on the table for a member of said means, and a hinged connection for said table with said cover. 60

5. A cover for a cabinet of the character stated having in its top an opening, a section separate from the surrounding side wall of the cover adapted to occupy said opening and form a closure therefor and comprising a table, means on the cabinet for movably sustaining said table, guides on the table for a member of said means, and a locking device for the table adapted to be engaged with said member. 70

PASQUALE DELLA TORRE.
